UNITED STATES PATENT OFFICE.

ROBERT A. RUSSELL, OF RIDGEWOOD, NEW JERSEY, ASSIGNOR TO PARAGON CAN & CAP COMPANY, INC., OF PATERSON, NEW JERSEY, A CORPORATION OF NEW YORK.

RECEPTACLE CLOSURE.

Application filed May 19, 1926. Serial No. 110,178.

This invention relates to improvements in receptacle closures or caps, with the object in view of providing a re-closure which may be readily applied to and removed from the receptacle, and will, when so applied, be held firmly in place against accidental displacement.

Another object consists in providing such a re-closure as may be used indefinitely without any appreciable decrease in the firmness with which it grips the receptacle to which it is applied.

A further object consists in providing such a re-closure having a double, successive gripping action.

A still further object consists in providing certain improvements in the form, construction and arrangement of the parts whereby the above mentioned and other objects may be attained more effectively than heretofore.

A practical embodiment of my invention is represented in the accompanying drawings, in which

Fig. 1 represents a side view partly in vertical section showing the re-closure in position upon the receptacle before removal of the seal, which is here represented as an ordinary "crown" seal,

Fig. 2 represents a vertical section showing the receptacle and re-closure in effective engagement therewith, after removal of the seal.

The receptacle, of which only the upper portion is shown, is denoted by 1, and represents, by way of example, an ordinary catsup bottle. It is provided with an annular projecting bead 2, located a short distance from the mouth of the receptacle, and with an annular enlargement 3 intermediate the bead and the mouth. The bead 2 and enlargement 3 may be of ordinary size and shape, such as are commonly fashioned upon bottles of this nature.

The re-closure 4 may, if desired, be of integral construction or formed in any other approved manner. It is here represented, by way of illustration, as of the two-piece type, comprising a body portion 5 and a top 6, seamed together in a well known manner at 7. The lower edge may advantageously be rolled or folded as indicated at 8, which serves the double purpose of concealing the cut edge of the material forming the body of the cap and of reinforcing that edge against accidental distortion.

Additionally, the closure 4 may be composed of some relatively elastic or springy material, such, for instance, as lacquered tin, while the receptacle 1 will generally and naturally be composed of some unyielding, co

vitreous material, such as glass.

The cap body 5 is of a size to slide easily over the enlargement 3 and is provided, at some distance from its top, with an annular series of elongated indentations arranged in pairs as shown at 9, 9. These indentations are preferably so distanced from the top and bottom of the cap that they will lie just below the enlargement 3 when the cap is applied to the receptacle with its lower edge 8 impinging firmly upon the annular bead 2, thus limiting the downward movement of the cap.

The indentations 9, 9 thus form, on the inside of the cap, a series of ridge-like projections which spring aside in passing over the enlargement 3 to allow the cap to be applied, and yet offer sufficient resistance by their engagement with the lower part of the enlargement 3 to prevent accidental displacement of the cap.

10 is a seal of any usual form, here shown as a "crown" seal.

When it is desired to open a new bottle sealed as shown in Fig. 1, the re-closure 4 is removed by hand, the seal 10 is removed by a suitable instrument and the contents of the receptacle is available for use. After pouring out the desired quantity, the receptacle is re-closed by applying the closure 4 as shown in Fig. 2. In this position dust-proof contact is formed between the lower edge 8 and the annular projecting bead 2 of the receptacle. The indented portions 9, 9 engage the enlargement 3 below its point of greatest circumference and so operate to hold the closure firmly down upon the bead 2 and insure the tightness of the joint just mentioned.

The arrangement of the indentations 9, 9 in pairs as shown has been found of great advantage in several respects. Each member of a pair serves to strengthen the other and the firm gripping action resulting therefrom does not diminish to any appreciable degree during the whole useful life of the filled receptacle; in this respect there results a substantial improvement over caps having a series of single depressions which have been found to soon decrease in useful-

ness by the flattening out of the depressions whereupon the gripping feature is weakened and practically only a slip-on cap remains.

A further result of providing pairs of indentations is that the cap may be held against accidental displacement altho not pushed completely home upon the receptacle neck. The lower series of indentations will engage the receptacle to an appreciable degree even when the cap is carelessly applied. It is evident that in a cap having but a single series of gripping parts (which must correspond to the upper series in the cap here shown), there can be no effective gripping of the receptacle until the cap has been completely seated.

The narrow, ridge-like form of the indentations enables them to resist quite stiffly any deforming forces, with the result that a much more positive engagement is secured than that obtained by a flat plateau-like area such as has sometimes been suggested for this purpose.

It will be understood that various changes may be resorted to in the form, construction and arrangement of the several parts without departing from the spirit and scope of my invention; and hence, I do not intend to be limited to the details herein shown and described except as they may be included in the claims.

What I claim is:

1. A sheet metal receptacle closure including a cylindrical body portion provided with a plurality of sets of horizontally disposed elongated indentations spaced from the top of said body portion, the indentations of each set forming on the inside of the body portion ridge-like projections adapted to engage the wall of a receptacle to hold the closure removably in place thereon, the distance between adjacent indentations of each set being not greater than substantially one twentieth of the circumference of said cylindrical body portion.

2. A sheet metal receptacle closure including a cylindrical body portion provided with an annular series of sets of horizontally disposed elongated indentations spaced from the top of said body portion, the indentations of each set forming on the inside of the body portion ridge-like projections adapted to engage the wall of the receptacle to hold the closure removably in place thereon, the distance between adjacent indentations of each set being substantially less than the length of said indentations.

In testimony, that I claim the foregoing as my invention, I have signed my name this 14th day of May, 1926.

ROBERT A. RUSSELL.
